US0D1090567S

(12) **United States Design Patent** (10) **Patent No.:** **US D1,090,567 S**
(45) **Date of Patent:** **** Aug. 26, 2025**

(54) **CIRCULAR CONTROLS SURROUNDING A DISPLAY SCREEN**

(71) Applicant: **Alfred Kaercher SE & Co. KG**, Winnenden (DE)

(72) Inventors: **Michael Meyer**, Schwalkheim (DE); **Waldemar Kunz**, Waiblingen (DE)

(73) Assignee: **Alfred Kaercher SE & Co. KG**, Winnenden (DE)

(**) Term: **15 Years**

(21) Appl. No.: **29/866,471**

(22) Filed: **Sep. 14, 2022**

(30) **Foreign Application Priority Data**

Mar. 21, 2022 (WO) WIPO114930

(51) **LOC (15) Cl.** **15-05**

(52) **U.S. Cl.**
